CHARGING AND CLOSING APPARATUS FOR CONCRETE MIXERS

John W. Lendved and William H. Buelow, Milwaukee, Wis., assignors to Chain Belt Company, Milwaukee, Wis., a corporation of Wisconsin

Application October 2, 1951, Serial No. 249,294

19 Claims. (Cl. 259—161)

1

This invention relates, generally, to rotary drum concrete mixers or the like and more particularly to improved hopper and closure apparatus for cooperating with the charging opening of a rotary mixing drum.

A general object of the present invention is to provide an improved combined charging hopper and door for the charging opening of a rotary drum concrete mixer.

Another object of the invention is to provide improved operating and control apparatus for actuating a combined hopper and door structure on a concrete mixer.

Another object is to provide actuating mechanism for a combined hopper and door for a concrete mixer charging opening, including an arrangement to prevent interchanging movement of the hopper and door except when retracted from the charging opening.

A further object is to provide improved actuating mechanism for a combined charging hopper and door arranged to lock the hopper and door in selected position.

According to the present invention, a rotary mixing drum, such as used in a concrete mixer of the inclined axis high discharge type presenting a coaxial charging opening at its upper end, is provided with an improved combined charging hopper and door structure. This combined structure is mounted for bodily movement toward or from the drum charging opening through pivoting movement of a supporting yoke, the structure being rotatably mounted in the yoke for tilting therein to either of two positions for presenting the hopper element or the door element to the drum opening selectively. The combined hopper and door is actuated by interlocked control apparatus arranged for operation from a readily accessible position and functioning selectively to perform the movements that select the hopper or the door and move the selected element into cooperating engagement with the drum charging opening. The coordinated control mechanism is so interlocked that the door and hopper structure can be tilted only while the structure is in a position remote from the charging opening. Locking apparatus is provided for locking the combined hopper and door in selected position to prevent accidental displacement.

The foregoing and other objects of this invention will become more fully apparent as the following detailed description of an exemplary embodiment thereof is read in conjunction with the accompanying illustrative drawings, wherein:

Figure 1 is a view in left side elevation of an improved combined hopper and door structure and associated control apparatus embodying the present invention, together with the rear portion of a truck-mounted concrete mixer to which it is applied;

Fig. 2 is a view similar to Fig. 1 but showing

2

the combined hopper and door structure inverted and including a broken line position illustrating further movements;

Fig. 3 is an enlarged fragmentary view of parts of the structure shown in Fig. 2, some parts having been broken away to disclose internal structure;

Fig. 4 is an enlarged fragmentary detail view in section through the dust shield shown in elevation in Fig. 3;

Fig. 5 is a view of the mixer structure in rear elevation with the combined hopper and door disposed in the position shown in solid lines in Fig. 2;

Fig. 6 is an enlarged detailed view in vertical transverse section through the control gear box, taken on the plane represented by the line 6—6 in Fig. 5; and

Fig. 7 is a view in longitudinal section through the gear box, taken on the plane represented by the line 7—7 in Fig. 6.

The embodiment of the invention set forth herein by way of an illustration of a practical structural manifestation of the inventive concept constitutes an improved combined charging hopper and closure door for cooperating with the charging opening of a rotary mixing drum such as the drum of a concrete mixer of the truck-mounted high discharge type represented in the drawings.

30 The particular truck-mounted high discharge mixer illustrated in part in the drawings by way of example may be of the type fully shown and described in the copending application of John W. Lendved filed August 3, 1951, Serial No. 240,141, although it is to be understood that the improved combined charging hopper and door apparatus may be applied with equal advantage to various other mixing drums of different construction.

40 Referring more specifically to the drawings and particularly to Figs. 1 and 2 thereof, the illustrative concrete mixer with which the improved hopper and door mechanism is arranged to cooperate is represented by a mixer drum 10 and its supporting frame 11, only the rear portions of which are shown. As explained in the co-pending application, the mixer drum 10 is rotatably supported in the cooperating truck-mounted frame 11 with its rear or discharge end in elevated position, a rear upright or frame member 21 constituting the principal portion of the frame 11 illustrated in the drawings. The mixing drum 10 is rotatable about its longitudinal axis 12 which is inclined upwardly and rearwardly in such a

50 manner that the drum presents a coaxial charging and discharging opening 16 in an elevated position at the rear of the motor truck on which the mixer is mounted. As more fully explained in the previously mentioned copending application, the drum 10 is rotatably supported or cradled 55 as shown in Fig. 5 in the rear upright member 21

of the frame 11 upon a pair of rollers 22 journaled in spaced relationship in the frame and cooperating with a cylindrical bearing ring or trackway 23 on the periphery of the drum 10. As best shown in Fig. 3, the drum 10 is provided on its internal surface with spirally arranged mixing blades 27 which operate to tumble and mix the concrete and to either feed it inwardly or eject it outwardly for discharging through the elevated discharge opening 16, depending upon the direction of rotation of the drum. As shown, the mixing blades 27 are provided along their inner edges with transverse or circumferential lips 28.

According to the present invention, the elevated charging and discharging opening 16 is adapted for functioning in the charging and mixing phases of a concrete mixing cycle through cooperating with a combined hopper and door structure or assembly 31. The structure 31 includes a closure or door element 32 shown engaged to cover the opening 16 in Fig. 1 and a charging hopper 33 shown in Fig. 2 disposed in cooperating relationship with the charging opening 16 in the drum 10, an extending chute element 34 at the lower edge of the hopper serving to guide material fed through the hopper into the drum opening. As appears in the drawings, the door 32 and the hopper 33 are joined together in back-to-back relationship to constitute a unitary structure, either element of which may be engaged with the drum opening 16 selectively thereby to facilitate charging the drum or, alternatively, to retain the charged material in the drum during mixing and transporting thereof. To provide for the interchange of these elements, the assembly 31 is mounted for tilting movement in such a manner that it may be inverted to present either the door 32 or the hopper 33 to the opening 16 alternatively as may be desired. Furthermore, the assembly 31 is arranged for bodily swinging movement in order that it may be lifted or retracted from the opening 16 and lowered or advanced toward the opening, the arrangement being such that either the door or the hopper may thereby be moved into engagement with the opening, depending upon which is presented toward it at the time.

To provide for the desired bodily movement toward or from the opening 16, the combined hopper and door structure 31 is movably supported on the mixer frame 11 by means of a rotatable transverse shaft 35 journaled in bearings 36 mounted on the outer top rear corners of the mixer frame 11 above the upper edge of the charging opening 16 in the drum 10. As best shown in Fig. 5, the cross shaft 35 has fixed to it a pair of spaced, radially extending, depending, parallel arms 37 that support the combined structure 31 between their outer ends for bodily pivotal movement thereof toward or from the opening 16 when the shaft 35 is turned. The cross shaft 35 and the arms 37 constitute in effect a supporting yoke with the outer ends of its arms rotatably engaging trunnions 38 on the opposite sides of the combined structure 31 to provide for tilting movement of the structure about the trunnion axis to present either the door 32 or the hopper 33 to the drum opening 16.

As shown in the drawings, the hopper element 33 has secured to its lower side or back a pair of spaced brackets 39 that are adjustably connected to a transverse supporting bar 40 that carries at its respective ends offset arms 41 from which the trunnions 38 project into bearings at the outer

ends of the pivoting arms 37. By this arrangement, the hopper 33 may be tilted upon the trunnions 38 to such position that its lower end or chute 34 may be introduced into the drum opening 16 between the lips 28 on the inner edges of the spiral mixing blades 27 as shown in Fig. 3, the proper position of the discharge chute 34 of the hopper, relative to the blade lips 28 being established by adjusting the mounting of the brackets 39 upon the supporting bar 40.

To prevent the escape of dust from that portion of the opening 16 beneath the chute 34 while the drum is being charged, the hopper 33 is provided with a semicircular depending dust shield or plate 42. As shown in detail in Fig. 4, the outer edge of the dust shield 42 is provided with a peripheral dust skirt 43 of rubber or like flexible material that yieldably engages the edge of the drum opening 16 and maintains close engagement therewith while permitting relative movement when the drum is rotated while material is being charged into it.

From the foregoing it will be understood that by pivotally revolving the combined hopper and door structure 31 bodily about the axis of the cross shaft 35 and by tilting it about the trunnions 38, either the hopper element or the door element may be presented to and advanced into cooperating relationship with or retracted from the drum opening 16 selectively.

The closure element or door 32 is constituted by a dished circular cover plate that engages the edge of the drum opening 16 for closing it completely in the manner shown in Fig. 1 during mixing or transporting of the concrete. In order that the door element 32 may rotate with the drum 10 during the mixing operation, the door is rotatably mounted on a stub shaft or stud 44 secured to and projecting radially from the supporting bar 40 at the back of the hopper 33. As best shown in Fig. 3, the stub shaft 44 passes through an enlarged opening 45 in the center of the door 32 into a cylindrical cup-like housing 46 secured over the opening 45 and projecting inwardly of the door 32. The stub shaft 44 is preferably provided on its end within the door with an antifriction bearing 47 that is supported within the housing 46 by a disk or diaphragm 48, the bearing being yieldably retained within a cavity in the disk 48 by means of a pressure plate 49 that is urged against the bearing by springs 50 seated in the bottom of the housing 46. By this arrangement the cover 32 may be forced into firm engagement with the end of the mixing drum 10 to close the charging opening 16, the spring pressed plate 49 yielding as may be necessary to adapt the door to irregularities that may be present on the edge of the drum, in a manner to maintain a tight fit between the door and the drum. The bearing 47 thereby adapts itself to permit free rotation of the door with the drum while maintaining the door in close engagement with the drum through the resilient action of the springs 50. By arranging the bearing housing 46 inwardly of the door 32 as shown in the drawing, it is possible to mount the door close to the back of the hopper 33, thereby maintaining the overall dimensions of the combined unit 31 at a minimum to facilitate tilting movement thereof in presenting the door or the hopper alternatively to the drum opening 16.

As shown in the drawings, the cover plate constituting the door 32 is provided with three axially projecting centering lugs 51 equally spaced about its periphery. The three lugs 51 engage the inner

edge of the drum opening 16 and guide the door into concentric relationship therewith as it is urged into closed position by the resilient rotary supporting structure.

Tilting movement of the hopper and door assembly 31 is effected by means of a sprocket 52 secured to the outer end of the trunnion 38 on the left side of the assembly as shown in Fig. 5. Aligned with the sprocket 52 on the trunnion is a complementary sprocket or drum 53 the hub of which is rotatably mounted on the shaft 35, the two sprockets being interconnected by a transmission chain 54. By this arrangement, both the tilting movement of the assembly 31 on the trunnions 38 and its bodily pivoting movement about the shaft 35 may be effected by concentrically arranged controls, since both the shaft 35 and the pinion 53 may rotate independently on the same axis.

Selective operation of the concentric controls is effected by a single hand wheel 56 that is rotatably mounted at the left side of the machine in a readily accessible position on a gear box 57 that is secured to the lower left upright of the frame member 21 below the discharge end of the drum 10. For effecting the bodily pivoting movement of the assembly 31 toward or from the drum opening 16, there is provided a control rod 58 which extends from the gear box 57 upwardly and is pivotally attached at its upper end to the outer end of an arm 59 fixed to and extending radially rearwardly from the end of the shaft 35 as shown in Figs. 1 and 2. Tilting movement of the assembly 31 about its trunnion axis is effected by a similar but offset control rod 61 that extends upwardly from the gear box 57 and is pivotally connected at its upper end to the outer end of an arm 62 secured to and extending radially forwardly from the hub of the sprocket 53 that is rotatably mounted on the shaft 35.

In effecting an interchange of the positions of the door element and the hopper element, the first operation is to move the control rod 58 upwardly by rotation of the hand wheel 56, thereby acting upon the radial arm 59 in a manner to turn the shaft 35 counterclockwise, thus pivoting the arms 37 and lifting the assembly 31 bodily outward and upward from the opening 16 in the drum 10. After the assembly 31 has been retracted in this manner to its elevated position, the control rod 61 is moved downwardly thereby turning the arm 62 and the sprocket 53 counterclockwise and through action of the chain 54 and the sprocket 52, causing the assembly 31 to be tilted upon its trunnions to the position shown in broken lines in Fig. 2. The control rod 58 may then be moved downwardly by operation of the hand wheel 56 to pivot the shaft 35 and lower the hopper element 33 into engagement with the charging opening 16, as shown in solid lines in Fig. 2.

Coordinated movements of the control rods 58 and 61 are effected by interlocked actuating mechanism within the gear box or case 57 and shown in detail in Figs. 6 and 7. As shown in Fig. 7, the actuating hand wheel 56 is rotatably mounted in a suitable bearing 64 secured to the outer face of the gear box or case 57. The hub of the hand wheel 56 is hollow and is internally splined to receive a shaft 65 which is axially slideable therein and extends through the bearing 64 into the gear case 57. As shown in Fig. 7 the shaft 65 is provided on its inner end with a pinion 66 and on its outer end with an actuating knob 67 secured thereto by a pin 68. By manipulating

the knob 67, the shaft 65 may be moved endwise to shift the pinion 66.

With the shaft 65 in the inner position as shown in Fig. 7, the pinion 66 meshes with an inner gear wheel 69 that is fixed on a shaft 70 rotatably mounted in the gear case 57 and extending therefrom at the rear side thereof. The extending end of the shaft 70 is provided with a crank arm 71 the outer end of which is pivotally connected to the lower end of the control rod 58, the arrangement being such that when the hand wheel 56 is turned, the pinion 66 turns the gear 69 and the crank 71 moves the control rod 58 up or down to effect bodily pivoting movement of the assembly 31 toward or from the charging opening 16 of the drum 10. Starting from the position of the mechanism shown in Figs. 2 to 7, in which the hopper is shown applied to the drum opening 16, rotation of the hand wheel 56 in the clockwise direction causes the gear 69 and crank 71 to turn counterclockwise thereby moving the rod 58 and the assembly 31 upward from the full line position to the broken line position shown in Fig. 2. In moving the assembly 31 into the retracted broken line position, the crank 71 passes through its top dead center position and comes to rest against a stop 72 (Fig. 6), in an over-center position thereby retaining the assembly 31 in its elevated position.

By pulling outward on the control knob 67, the pinion 66 may be withdrawn from meshing engagement with the inner gear wheel 69 and shifted into meshing engagement with an outer gear wheel 74 fixed on a shaft 75 likewise rotatably mounted in the gear box 57 with one end projecting at the rear side thereof. The projecting end of the shaft 75 is similarly provided with a crank arm 76 that is pivotally connected at its outer end to the lower end of the control rod 61. Upon turning the hand wheel 56 counterclockwise, the pinion 66 is now caused to rotate the gear 74 and the crank arm 76 clockwise thereby moving the control rod 61 upwardly from the position shown in Fig. 2 to the position shown in Fig. 1 which results in turning the arm 62 and the sprocket 53 clockwise to effect clockwise tilting of the assembly 31 about its trunnion axis, thereby presenting the door element 32 toward the drum opening 16. In moving into the upper position, the crank 76 passes through its upper dead center position and into over-center engagement with the other side of the stop 72, thereby retaining the assembly in the selected position. The pinion 66 may then be moved back into meshing engagement with the inner gear wheel 69 by pushing inward on the actuating knob 67. Instead of employing the knob 67 for shifting the pinion 66, the hand wheel 56 may be secured directly to the shaft 65 in place of the knob, the shaft then being rotatably and slideably mounted in the bearing 64. Under these circumstances, the hand wheel itself is moved axially to effect end-wise shifting of the shaft 65 and the pinion 66.

When the pinion 66 is shifted out of engagement with the gear 74 by inward movement of the shaft 65, a locking latch or plunger 78 carried on the outer end of a pivotally mounted spring urged arm 79 is released for movement upward into locking engagement with the teeth of the gear wheel 74 to prevent accidental displacement of the assembly from its tilted position through operation of external forces. With the pinion 66 again engaged with the inner gear 69, the hand wheel 56 may then be turned counterclockwise to cause the crank 71 to turn out of

its over-center position and move the control rod 58 downward thereby advancing the assembly 31 downward toward the drum 10.

As soon as the inner gear 69 is turned from the elevated or fully retracted position, one end of an arcuate shroud plate or segment 81 secured to the face of the gear 69 moves in front of the face of the meshing pinion 66 thereby constituting an interlocking or interference member which prevents the pinion from being shifted out of engagement with the gear 69. As turning of the hand wheel is continued, the cover element 32 is brought down into cooperating engagement with the end of the drum 10 for closing the discharge opening 16, as shown in Fig. 1, to adapt the mixer for the mixing and transporting operations. The cover is retained in the closed position by the force of gravity and it may be locked in this or in other desired partially open positions, by means of a spring pressed locking plunger 83 that engages between the teeth of the gear 69, as shown in Fig. 6.

When it is desired to open the door 32 after the mixing operation for discharging concrete, the gear 69 is released by withdrawing the plunger 83 through operation of a hand lever 84 that is pivotally mounted on the outer end of the plunger and is provided with a cam surface 85 that cooperates with the outer end of a tubular housing 86 extending from the right side of the gear box 57 in a manner to withdraw the plunger by compressing a spring 87 within the housing 86. As shown, the spring 87 encircles the plunger 83 and is arranged to urge it into engagement with the gear teeth. With the plunger 83 withdrawn, the gear 69 may be turned to elevate the hopper and door assembly 31, whereupon the load of concrete may be discharged from the drum 10 through the discharging opening 16 by rotating the drum in the appropriate direction.

Since the shroud plate 81 prevents shifting of the pinion 66 out of engagement with the gear 69, the pinion 66 cannot be engaged with the gear 74 while the assembly is in lowered position and consequently the door and hopper cannot be tilted upon the trunnion axis until after the assembly is elevated out of interfering relationship with the end of the drum 10. As the assembly 31 arrives at its elevated position, the end of the shroud plate 81 moves past the outer face of the pinion 66 thereby freeing it for subsequent shifting movement. With the assembly elevated, the locking plunger 83 may be moved inward to lock the gear 69 by action of the spring 87 upon moving the cam lever 84 to the position shown in Fig. 6, thereby retaining the assembly in elevated position.

The load of concrete having been discharged through the opening 16, and the pinion 66 now being free from interference with the shroud 81, the pinion may be moved outwardly by pulling out on the actuating knob 67. As the pinion 66 approaches meshing engagement with the outer gear wheel 74, it engages a sloping or cam surface 89 on the spring urged arm 79 supporting the locking plunger 78, and forces it downward to move the plunger out of locking engagement with the teeth of the gear 74. This frees the gear 74 for rotation by the pinion 66 to tilt the assembly to the position shown in broken lines in Fig. 2 for substituting the hopper element 33 for the door element 32 as the active member of the combination. After the assembly 31 has been

tilted, the pinion 66 may then be shifted inwardly by the knob 67 thereby releasing the spring pressed arm 79 for moving the plunger 78 again into locking engagement with the gear wheel 74, the pinion 66 meanwhile moving past the end of the shroud ring 81 into meshing engagement with the inner gear 69. After the locking plunger 83 is again withdrawn, further movement of the hand wheel 56 then results in lowering the hopper into engagement with the charging opening as shown in Figs. 2 and 5, the interlocking shroud plate 81 meanwhile obviating the possibility of further tilting movement of the assembly 31.

By substituting suitable cam mechanism or automatic shifting mechanism for the gearing shown in Figs. 6 and 7, the operation of elevating and tilting the assembly 31 for interchanging the hopper and door elements may be accomplished by continuous rotation of the hand wheel 56 without manual shifting of gearing. However, this would result in sacrificing a desirable degree of flexibility in operation which accrues from providing for manual shifting of the selective pinion 66. Furthermore, operation of the mechanism by power may be effected by providing a power drive to the pinion shaft 65 or by substituting hydraulic or air actuating mechanism with suitable interlocking controls for the mechanically interlocked mechanism in the gear case 57.

From the foregoing description and explanation of the operation of the improved concrete mixer charging apparatus set forth herein, it is apparent that there has been provided by the present invention a new and more convenient arrangement for cooperating with the charging opening of a truck-mounted concrete mixer whereby either a charging hopper element or a closure element may be applied to the opening through interchanging the two elements of a combined hopper and door assembly by the co-ordinated operation of interlocked actuating mechanism.

Although a specific embodiment of the invention has been described in detail by way of a full disclosure of preferred apparatus for practicing the invention, it is to be understood that the particular mechanism herein set forth constitutes merely one exemplification of the invention and that the structure shown may be modified to adapt it to various mixers and to their conditions of operation without departing from the spirit and scope of the invention as defined by the subjoined claims.

An exemplary embodiment of the invention having now been fully described, we claim as our invention:

1. In a concrete mixer of the elevated discharge type having a drum mounted for rotation upon an inclined axis and presenting a single charging and discharging opening concentric with its axis and at its elevated end, a frame arranged to support said rotatably mounted drum, a shaft rotatably mounted in said frame transversely thereof adjacent to and above said drum opening, a pair of arms fixed to and extending rearwardly and downwardly from said shaft in parallel relationship at opposite sides of said drum opening respectively, a combined hopper and door structure disposed between and rotatably mounted on the outer ends of said parallel arms and comprising a hopper element and a door element presentable alternatively toward said drum opening through tilting movement thereof relative to said drums,

a sprocket mounted on said hopper and door structure concentric with its axis of rotation, a complementary sprocket rotatably mounted on said shaft, a transmission chain operatively interconnecting said sprockets in such a manner that rotation of said sprocket on said shaft effects tilting movement of said hopper and door structure, and control mechanism operatively connected to rotate said sprocket or said shaft selectively, whereby said hopper and door structure may be tilted to present said hopper element or said door element toward said drum opening and said arms may be pivoted to move said structure bodily to engage said hopper element or said door element with said drum opening.

2. In a concrete mixer, a rotatably mounted mixing drum presenting a charging and discharging opening, a combined hopper and door structure disposed to cooperate with said drum opening to facilitate charging said drum or alternatively to close said opening during mixing, trunnions arranged to carry said combined hopper and door structure in a manner to provide for tilting said structure to present either the hopper element or the door element to said drum opening selectively, and pivotally mounted arms arranged to support said trunnions for rotary movement thereon, said arms being pivotally supported above said drum opening and operative when pivoted to move said hopper and door structure bodily toward or from said drum opening selectively.

3. In a concrete mixer, a mixing drum presenting in one end a charging and discharging opening, a frame arranged to support said drum for rotation about an axis concentric with said opening, a yoke pivotally mounted on said frame above said drum for swinging movement toward or from said drum opening, and a combined hopper and door rotatably mounted in said yoke and comprising a hopper element and a door element arranged to be presented alternatively toward said drum opening by appropriate tilting movement thereof in said yoke, the arrangement being such that whichever of said elements is presented toward said drum opening may be moved into cooperative relationship therewith by appropriate pivotal movement of said yoke relative to said frame.

4. In a concrete mixer having a mixing drum disposed with one end elevated and presenting a charging opening, a combined hopper and door structure disposed to cooperate with said charging opening, apparatus for effecting lowering or elevating movement of said combined structure toward or from said charging opening, apparatus for effecting tilting movement of said structure to present the hopper or the door toward said charging opening alternatively, and interlocking control mechanism interconnecting said actuating apparatus and including an interference member arranged to provide for operation thereof in such a manner as to effect tilting movement of said combined hopper and door structure only when said structure is elevated away from said charging opening, whereby interference between said drum and said structure during tilting thereof is obviated.

5. In a concrete mixer or the like, a frame adapted for mounting on a truck, a mixing drum rotatably mounted in said frame with its axis inclined upwardly and rearwardly to present an elevated discharge opening at the rear of the truck, a supporting shaft journaled transversely of said frame above said elevated opening, supporting arms attached to and extending radially

from said shaft, a combined hopper and door rotatably mounted on said arms for tilting movement to present either a hopper element or a door element toward said drum opening, a unitary control mechanism mounted on said frame below said drum in a readily accessible position and including pivoting mechanism and tilting mechanism, linkage operatively interconnecting said control mechanism with said shaft and with said combined hopper and door in such a manner that said shaft may be pivoted to raise or lower said hopper and door relative to said drum opening or said combined hopper and door may be tilted to present the one or the other to said drum opening, and interlocking apparatus operatively associated with said pivoting and tilting control mechanism and including an interference member movable with said pivoting mechanism and operative to prevent tilting movement of said combined hopper and door by said tilting mechanism except when said combined hopper and door is pivoted to raised position away from said drum opening.

6. In a concrete mixer of the inclined axis type presenting an elevated coaxial charging and discharging opening, a combined hopper and door structure presenting a hopper element and a door element adapted for alternative application to said opening, and interlocked control mechanism operative to move said hopper and door structure bodily toward or retract it from said mixer opening and including actuating elements operative only when said structure is retracted from said opening to position said structure for presenting either said hopper element or said door element selectively for movement into cooperating relationship with said opening.

7. A concrete mixer comprising a frame, a mixing drum rotatably mounted in said frame and presenting a charging and discharging opening concentric with its axis of rotation, a shaft rotatably mounted in said frame transversely thereof adjacent to and above said drum opening, a pair of supporting arms attached to and extending rearwardly and downwardly from said shaft in spaced relationship, and a combined hopper and door disposed between and rotatably mounted on said arms and constituted by a hopper element and a door element arranged to be presented toward said drum opening alternatively by appropriate tilting movement thereof relative to said arms and to be moved bodily toward or from said drum opening by appropriate pivotal movement of said arm carrying shaft, the arrangement being such that either said hopper or said door may be applied to said drum opening selectively.

8. In a concrete mixer having a frame and a mixing drum rotatably mounted in said frame and presenting a charging and discharging opening, a charging hopper disposed to cooperate with said drum opening in facilitating charging of said drum, a door likewise disposed to cooperate with said drum opening to close it during a mixing operation, means movably supporting said hopper and said door on said frame, and control linkage operatively arranged to move the one or the other of said hopper and said door into register with said drum opening selectively, said control linkage including an interference member arranged to interlock said control linkage in such a manner that interference between said hopper, said door and said drum is obviated.

9. In a concrete mixer having an inclined mixing drum presenting a charging opening in its elevated end and a cooperating combined hopper

11

and door tiltable to present a charging hopper or a closure door to said drum opening alternatively, a control mechanism for operating said combined hopper and door comprising a gear box including a gear for effecting tilting movement of said combined hopper and door relative to said mixing drum opening and another gear for effecting lowering or elevating movement of said combined hopper and door bodily towards or from said mixing drum opening, linkage operatively interconnecting said gears with said combined hopper and door structure in a manner to effect said movements respectively upon turning movement of the appropriate one of said gears, a shiftable pinion disposed to be shifted into engagement with the one or the other of said gears alternatively to effect the corresponding movement of said combined hopper and door, a hand wheel operatively connected to effect turning movement of said pinion, and an interlocking interference plate associated with said hopper and door elevating gear and operative to prevent disengaging movement of said pinion from said gear except when said gear is in the position corresponding to the fully elevated position of said combined hopper and door, whereby said pinion cannot be shifted into engagement with said hopper and door tilting gear except when said hopper and door is in elevated position thereby preventing tilting movement thereof in any position in which interference with said mixing drum would otherwise occur.

10. In a concrete mixer of the inclined axis rotary drum type presenting a charging and discharging opening at its elevated end, a combined hopper and door structure for cooperating with said opening, said combined structure comprising a hopper element for facilitating charging the drum through said opening and a door element to close said opening during mixing, said elements being arranged to engage said opening alternatively, a yoke movably supporting said combined hopper and door structure for movement to present said hopper element or said door element to said opening selectively, a frame movably supporting said yoke for bodily movement of said combined hopper and door toward or from said drum opening to engage said hopper or said door with said drum opening, control apparatus operatively arranged to effect movement of said combined hopper and door relative to said yoke and bodily movement thereof relative to said drum opening, and interlocking mechanism operatively associated with said control apparatus and including an interference member operative to prevent movement of said combined hopper and door relative to said yoke except after operation of said control apparatus to displace said combined hopper and door bodily from said drum.

11. Concrete mixing apparatus or the like including a drum presenting a charging opening, a combined hopper and door structure for cooperating therewith comprising a hopper element and a door element adapted to be engaged with said charging opening alternatively and joined to constitute a unitary structure, a yoke arranged to support said combined structure for tilting movement in a manner to present said hopper element or said door element toward said charging opening selectively, and a supporting frame pivotally supporting said yoke above said drum charging opening in a manner to provide for bodily pivotal movement of said combined structure toward or from said charging opening, the

arrangement being such that either said hopper element or said door element may be engaged with said charging opening by appropriate tilting movement of said combined structure in said yoke and pivotal movement of said yoke relative to said supporting frame.

12. In a concrete mixer of the rotary drum type with the drum presenting a charging and discharging opening, a combined hopper and door structure for cooperating with said opening, said combined structure comprising a hopper element for facilitating charging the drum through said opening and a door element to close said opening during mixing, said elements being arranged to engage said opening alternatively, a yoke movably supporting said combined hopper and door structure for tilting movement to present said hopper element or said door element to said opening selectively, and a shaft disposed above and transversely of the drum and pivotally supporting said yoke for bodily movement of said combined hopper and door toward or from said drum opening, whereby either said hopper or said door may be engaged with said drum opening selectively.

13. In a concrete mixer of the type having a rotary mixing drum presenting a coaxial charging and discharging opening, a combined hopper and door structure disposed to cooperate with said drum opening, said structure comprising a hopper element, a trunnion element adjustably mounted on the back of said hopper element and a circular door rotatably mounted on said trunnion element in back-to-back relationship with said hopper element; a yoke arranged to engage said trunnion element in a manner to support said combined structure for tilting movement about the axis of said trunnion element to present the one or the other of said hopper element and door element toward said drum opening, and a transverse shaft arranged above said drum opening and movably supporting said yoke in a manner to effect bodily movement of said combined structure toward or away from said drum opening, whereby either said hopper element may be disposed in adjusted cooperating relationship with said drum opening during charging of said drum or said door element may be engaged with said drum opening to rotate with said drum while maintaining said opening closed during mixing of the charge.

14. In a transit concrete mixer of the truck-mounted type, a mixing drum presenting a charging and discharging opening, a combined hopper and door structure arranged to cooperate with said drum opening to facilitate charging or alternatively to close said opening during mixing, controlling and actuating apparatus for positioning said combined structure relative to said opening, said apparatus comprising a gear wheel operatively connected to effect tilting movement of said combined structure for presenting the hopper or the door element thereof toward said opening and another gear wheel operatively connected to effect bodily movement of said combined structure toward or from said opening, a pinion slidably mounted for shifting into meshing engagement with the one or the other of said gear wheels selectively, actuating means connected to effect rotation of said pinion to operate the gear wheel with which it is meshed, an interference interlock associated with said bodily movement gear wheel and operative to prevent meshing of said pinion with said tilting gear wheel except when said combined struc-

ture is retracted from said opening, a manually actuated latch associated with said bodily movement gear wheel and selectively operable to lock said gear wheel for retaining said structure in selected position relative to said drum opening, and a resiliently urged latch associated with said tilting movement gear wheel and operative to engage and lock said gear wheel when said pinion is disengaged therefrom, said latch being positioned for retraction by said pinion in moving into engagement with said gear wheel thereby freeing said gear wheel for rotation by said pinion.

15. In a concrete mixer or the like, a frame adapted for mounting on a truck, a mixing drum rotatably mounted in said frame with its axis inclined upwardly and rearwardly to present an elevated discharge opening at the rear of the truck, a supporting shaft journalled transversely of said frame above said elevated opening, supporting arms attached to and extending radially from said shaft, a combined hopper and door structure rotatably mounted on said arms for tilting movement to present either a hopper element or a door element thereof toward said drum opening, a unitary control mechanism mounted on said frame beneath said drum in a readily accessible position, linkage operatively interconnecting said unitary control mechanism with said shaft and with said combined hopper and door structure in such a manner that said shaft may be pivoted to raise or lower said combined structure relative to said drum opening or said combined structure may be tilted to present the one or the other of said hopper and door elements to said drum opening, and a single actuating member operatively associated with said control mechanism and operative thereon to effect pivoting of said shaft to raise said arms and then tilting movement of said hopper and door structure when said structure is in raised position away from said drum opening.

16. In a concrete mixer having an inclined mixing drum presenting a charging opening in its elevated end and a cooperating combined hopper and door tiltable to present a charging hopper or a closure door to said drum opening alternatively, a control mechanism for operating said combined hopper and door comprising, a gear box including a gear for effecting tilting movement of said combined hopper and door relative to said mixing drum opening and another gear for effecting lowering or elevating movement of said combined hopper and door bodily towards or from said mixing drum opening, linkage operatively inter-connecting said gears with said combined hopper and door structure in a manner to effect said movements respectively upon turning movement of the appropriate one of said gears, a shiftable pinion disposed to be shifted into engagement with the one or the other of said gears alternatively to effect the corresponding movement of said combined hopper and door, and a single hand wheel operatively connected to effect turning movement of said pinion, whereby said pinion may be shifted into engagement with said hopper and door tilting gear or with said hopper and door elevating gear to provide either of said movements by operation of said single hand wheel.

17. In a transit concrete mixer of the truck-mounted type, a mixing drum presenting a charging or discharging opening, a combined hopper and door structure arranged to cooperate with said drum opening to facilitate charging or to

70

close said opening during mixing, controlling and actuating apparatus for positioning said combined structure relative to said opening, said apparatus comprising a gear wheel operatively connected to effect tilting movement of said combined structure for presenting the hopper or the door element thereof toward said opening and another gear wheel operatively connected to effect bodily movement of said combined structure toward or from said opening, a pinion slideably mounted for shifting into meshing engagement with the one or the other of said gear wheels selectively, and actuating means connected to effect rotation of said pinion to operate the gear wheel with which it is meshed.

18. In a transit concrete mixer of the truck-mounted type, a mixing drum presenting a charging or discharging opening, a combined hopper and door structure arranged to cooperate with said drum opening to facilitate charging or to close said opening during mixing, controlling and actuating apparatus for positioning said combined structure relative to said opening, said apparatus comprising a gear wheel operatively connected to effect tilting movement of said combined structure for presenting the hopper or the door element thereof toward said opening and another gear wheel operatively connected to effect bodily movement of said combined structure toward or from said opening, a pinion slideably mounted for shifting into meshing engagement with the one or the other of said gear wheels selectively, actuating means connected to effect rotation of said pinion to operate the gear wheel with which it is meshed, and a manually actuated latch associated with said bodily movement gear wheel and selectively operable to lock said gear wheel for retaining said structure in selected position relative to said drum opening.

19. In a transit concrete mixer of the truck-mounted type, a mixing drum presenting a charging or discharging opening, a combined hopper and door structure arranged to cooperate with said drum opening to facilitate charging or to close said opening during mixing, controlling and actuating apparatus for positioning said combined structure relative to said opening, said apparatus comprising a gear wheel operatively connected to effect tilting movement of said combined structure for presenting the hopper or the door element thereof toward said opening and another gear wheel operatively connected to effect bodily movement of said combined structure toward or from said opening, a pinion slideably mounted for shifting into meshing engagement with the one or the other of said gear wheels selectively, actuating means connected to effect rotation of said pinion to operate the gear wheel with which it is meshed, a resiliently urged latch associated with said tilting movement gear wheel and operative to engage and lock said gear wheel when said pinion is disengaged therefrom, and means operated by said pinion in moving into engagement with said gear wheel to retract said latch thereby freeing said gear wheel for rotation by said pinion.
